United States Patent Office

Des. 211,038
Patented May 14, 1968

211,038

FOOTED TUMBLER

James L. Wentzel, 6520 16th Lane,
St. Paul Park, Minn. 55071

Filed July 24, 1967, Ser. No. 7,947

Term of patent 14 years

(Cl. D36—8)

FIG. 1

FIG. 2

I claim:

The ornamental design for a footed tumbler, as shown.
